[57] CLAIM

The ornamental design for a skill game, as shown and described.

DESCRIPTION

FIG. 1 is a top and front perspective view of a skill game showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing of a playing disc is for illustrative purposes and forms no part of the claim.
